Filed Aug. 16, 1972, Ser. No. 281,004

Term of patent 14 years

Int. Cl. D9—06

U.S. Cl. D9—252

FIG. 1 is a perspective view of a corrugated strap fastener showing my new design with intermediate portion broken away for convenience of illustration.

FIG. 2 is a perspective view thereof in secured position, it being understood that the corrugations shown in full lines are continuous throughout the length of the inner face of the strip in the path indicated by dashed lines.

I claim:

The ornamental design for a corrugated strap fastener, as shown and described.
